REMOTE-CONTROL SYSTEM WITH
SUPERVISORY MEANS

George L. Haller, Dayton, Ohio

Application June 13, 1945, Serial No. 599,295

2 Claims. (Cl. 343—5)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to remote control radio systems and more particularly to a remote control system with known telemetering of selector position or telemetering proportional control indicating neutral balance of either operation side thereof.

The objects of the present invention comprise the provision of an improved system and method of remote control that is strongly positive in action under a wide range of atmospheric conditions; that is operable with extreme rapidity; that utilizes very accurate precision devices of a high degree of perfection; and that provides for an object in flight a repeat-back signal that informs a control station of the position of the object in flight.

With the above and other objects in view that will be apparent to those who are informed in the field of remote control radio devices, improved illustrative embodiments of the present invention in the form of circuits and associated devices are shown in the accompanying drawings, wherein:

Fig. 1 is a diagrammatical illustration of an overall embodiment of the present invention in operation;

Fig. 2 is a circuit diagram of a signal-controlled part of the present invention that is operated through a relay stepper;

Fig. 3 is a modified circuit diagram of a signal-controlled part of the present invention that is operated through a plurality of relays;

Fig. 4 is a fragmentary circuit diagram illustrating a proportionate-control system adaptation of the present invention; and

Fig. 5 is a frequency or pulse-repetition-frequency response graph diagram of the signal control in the proportionate-control system.

Referring more particularly to Fig. 1 the remote control system that comprises the present invention includes a control station 1, that, by means of signals radiated by an antenna 2, exercises operative control over a remote station 3, for example, an aircraft or the like. The equipment at the control station 1 functions as an interrogator and preferably comprises a usual combination of radio transmitter and receiver which indicate the azimuth and the elevation of the aircraft 3 by both reflected echo signals from the aircraft 3 at short range and at greater range by the stronger signals from a coded beacon 4

2

that is located in the aircraft 3 and shown in detail in Fig. 2. The transmitter at the control station 1 is also provided with the usual means for modifying pulse-repetition rates therefrom to provide a plurality of signals that are preferred for the satisfactory operation of the present invention. The equipment in the aircraft 3 preferably comprises the coded beacon 4, that acts as a transpondor in the reception and in the emission of signal from and to, respectively, the control station 1 and that is in electrical combination with a pulse-repetition-frequency selector 5 is interposed between the beacon 4 and a plurality of controls on the aircraft 3.

The relationship of the beacon 4 and the selector 5 is shown both in Fig. 1 and Fig. 2 of the drawings. The beacon 4, preferably in the aircraft 3, is of a usual type and comprises a receiving antenna 6 and a transmitting antenna 7. Referring now more particularly to Fig. 2, the output of the beacon 4 is disposed across an isolation stage in the selector 5, the return circuit being through ground. The isolation stage comprises an isolating electronic tube 10. The grid of the tube 10 is provided with a negative bias through a resistor 11 by a direct current source, such as battery 9, or the like. The plate of the tube 10 is provided with a positive voltage supply through the primary winding of a transformer 12. The grid of the tube 10 is connected through a battery 14 to ground. The positive post of the battery 9 and the negative post of the battery 14 are connected to the cathode of the tube 10 and to ground. In response to signals from the control station 1, the isolation stage conducts a signal from the beacon 4 through the primary winding of the transformer 12 to ground and prevents feed-back of signal into the beacon 4.

The primary winding of the transformer 12 passes the signal inductively from the isolation stage to a plurality of secondary windings of the transformer 12 which are connected individually across the grid-cathode circuits of a corresponding plurality of detecting electronic tubes 20, 21 and 22 that convert alternating current of the signal from the beacon 4 into direct current for the operation of relays to be described hereinafter. The secondary transformer windings that are disposed across the grid-cathode circuits of the tubes 20, 21 and 22 are individually tuned by capacitors 23, and 24 and 25, respectively, to provide the selector 5 with a plurality of frequency selective filters. The tubes 20, 21 and 22 are provided with negative grid bias by means of batteries 26, 27, and 28,

respectively, and with positive plate bias by means of a battery 30. The positive post of the battery 28 and the negative post of the battery 30 are connected to the cathode of the tube 22 and to ground.

Signals from the tube 20 operate a relay stepper 32 with its associated notched or pronged stepper wheel 31 and rotating switch arms 33, 34, and 35 that are operated from a common shaft that is indicated by a dash-line therebetween. The coding relay rotating switch arm 33 sweeps a desired plurality of signal contacts A, B, C, D, and E. The signal contacts A, B, C, D, and E individually determine the code of the signal that is generated by the radar coded beacon 4 and that is emitted from the antenna 7 thereof and that is received at the control station 1.

The wheel 31 of the relay stepper 32 preferably is notched or is provided with prongs or stops on its periphery that correspond with the number of contacts that are engaged individually by the switch arms 33, 34, or 35. The wheel 31 is geared with the rotating switch arms 33, 34, and 35 in any desired manner and so that when the coding relay switch arm 33 is on any one of the contacts A, B, C, D, or E, the functional switch arms 34 and 35 are on corresponding contacts of their respective switches that are indicated by corresponding letters that are primed and double primed, respectively, for ease in association with the contacts that are engaged by the switch arm 33.

The frequency selector tube 21 closes the relay 38 in its plate circuit upon the selective reception of a signal of a predetermined frequency or pulse repetition rate from the beacon 4 and passing through its respective filter comprising the capacitor 24 and the associated secondary transformer winding. In a similar manner, the tube 22 closes the relay 39 in its plate circuit upon the selective reception of a predetermined signal that is of a frequency that differs from the frequencies that are passed to either of the tubes 20 or 21 from its respective filter comprising the capacitor 25 and the associated secondary transformer winding. The energization of the circuit through the relay 38 takes effect upon the functional switch arm 34 contacting one of the channel contacts A', B', C', D', or E' that is selected by the stepping relay 32. The contact so made energizes another relay, or similar device in the aircraft 3 not shown for any suitable control purpose.

The remote control system that is disclosed herein preferably is an extension of a usual radar system wherein a plurality of control functions are provided for and made available for use. In conformity with the present invention, these control functions are under the substantially complete and positive control of the control station 1.

The radar at the control station 1 may be airborne or in a fixed location, as preferred, and is so modified that the pulse repetition rate thereof can be changed at will in discrete steps. An illustrative group of signal rates per second may comprise pulse repetition rates of 700 for normal, 800 for causing the operation of the stepper relay 32, 850 for the operation of the relay 38 and 900 for the operation of the relay 39. The normal or neutral pulse repetition rate is used preferably during the tracking of the aircraft 3 without the operation of any controls. The other pulse repetition rates are used for applying controls over the flight course of the

aircraft 3. The neutral pulse rate is selected so that a signal of that rate will not pass through any of the filters of the control equipment.

The radar beacon 4 in the aircraft 3 preferably is a substantially standard or known type of radar coded beacon and serves to aid in tracking the aircraft 3. The beacon 4 in the aircraft 3 is modified so that it responds to a signal at the pulse repetition rate of the radar at the control station 1. The beacon 4 is connected to the system of selective filters that are shown in Fig. 2, and which have previously been described.

The present system is limited to the number of discrete and separable frequencies which can be transmitted from the control station 1 to the aircraft 3 and also by the fact that the pulsed signal which originates from the radar at the control station 1 is so rich in harmonics, that, if the control frequencies are extended to more than one octave, serious difficulties may be encountered in differentiating a frequency which is a harmonic of another control frequency from that of the desired control frequency.

The present invention is directed toward the objective of extending the number of control functions by means of various combinations of a small number of basic pulse repetition rates. These combinations preferably are used in time sequence. Two signals of different pulse repetition rates preferably are not emitted simultaneously from the radar at the control station 1.

In the operation of the system that is contemplated hereby, a predetermined pulse repetition rate of the controlling radar at the control station 1 is derived in the usual manner from the radar, coded beacon 4 in the aircraft 3 and the return signal from the beacon 4 to the control station 1 is controlled by the position of the switch arm 33. The pulse repetition rate so derived from the beacon 4 is fed through the isolating tube 10 into one of the three electronic tubes 20, 21, or 22.

The tube 20 operates the stepper relay 32 and the stepper wheel 31 with its associated switches 33, 34, and 35, as previously described. The tube 21 operates the relay 38 and the tube 22 operates the relay 39. The channel controls in the aircraft 3 are powered in common through the relays 38 and 39 and the switch arms 34 and 35 from a "A" power source, as shown, to energize relay systems that operate to a predetermined degree and in pairs of functions. The pairs of functions exercised by the controls on the aircraft 3, may be, for example, up and down, right and left, accelerate and decelerate, and the like. A particular pair of functions is selected by the operation of the tube 20 and its associated stepper relay 32.

The circuits that are shown in Fig. 2 of the accompanying drawings are arranged to provide dual operations of five functions. The controls for carrying out the dual operations of these five functions are of a type in which there is control in either of two opposite senses and between which there is a neutral state. The five functions are illustrated by positions A, B, C, D and E; A', B', C', D' and E' and A'', B'', C'', D'' and E'' swept respectively by switch arms 33, 34 and 35.

The stepper relay 32 is adapted for selecting accurately a desired step on the wheel 31. The relative position of the stepper relay 32 with respect to the wheel 31 is relayed back to the control station 1 continuously from the beacon 4

through its antenna 7 by providing an individual or unique radar code response for each position of the stepper relay 32 with respect to the wheel 31. In the present system the radar beacon response is coded in some known manner and this coded response is received and recognized at the radar control station 1. The coding of the beacon 4 is accomplished by means well known in the art and will provide either different numbers, spacing or lengths of pulses, or any combination thereof, as a returning transmission from the beacon 4 to the control station 1. A particular adopted code serves to determine at all times the position of the stepper switch 32 with respect to the wheel 31. The code is changed by means of the coding relay switch associated with the arm 33, which is adapted to change the coded response of the beacon 4 to any one of the five different codes indicated by the five different stops on or notches in the periphery of the stepper wheel 31 corresponding to the letters A-E, inclusive, that are contacted by the switch arm 33. A particular code response from the beacon 4 depends upon the position of the coding relay switch arm 33 on its contacts A-E, inclusive, which is mechanically fastened to and operated by the same drive as are the functional switch arms 34 and 35, as indicated by the dash line therebetween.

In an illustrative control operation, the controlling radio at the control station 1 would be caused to search until a beacon response was obtained. The signal pulse repetition rate would then be switched to that frequency which would be accepted by the tube 20 and the tube 20 would function to operate the circuit of the stepper relay 32. This operation of the tube 20 would cause a change in the coded response of the beacon 4. This change would be immediately noticed at the control station 1.

The coded response change at the control station 1 imparts the information that the target has a control system. The operator at the control station then gives alternate impulses of the neutral pulse repetition rate and of the pulse repetition rate that controls the stepper switch 32, until the stepper switch 32 arrives at the required functional position, as indicated by the proper beacon response received at the control station 1.

Assuming, for purposes of illustration, that the circuits A', and A'' that are contacted by the functional switch arms 34 and 35, respectively, control a mechanism that governs the "up" and "down" positions of the elevators upon the aircraft 3, and that the circuits B' and B'' that are contacted by the same switch arms 34 and 35 control another mechanism that governs the "right" and "left" positions of the rudder on the aircraft 3. When so arranged, if the operator desires to control the aircraft 3 in azimuth, he sends the proper series of signal impulses from the control station 1 that are necessary to step the stepper switch 32 to its B position and the switch arms 34 and 35 to their B' and B'' positions, respectively, which are indicated as corrected by the coded response from the switch associated with the switch arm 33 through the beacon 4 and that are received at the control station 1.

If the operator at the control station 1 desires to turn the aircraft 3 toward the right, he changes the pulse repetition rate of the signal that is emitted from the control station 1 from the neutral frequency to that frequency which

energizes the filter circuit associated with the tube 21 so that it operates the relay 38. The operation of the relay 38 energizes the circuit connected to B' which, in turn and through the proper channel operates the functional controls which in turn operate an automatic pilot, or the like, that cause the aircraft 3 to turn toward the right. In a similar manner, the changing of the pulse repetition frequency so that the tube 22 is energized, operates the relay 39 and energizes the circuit connected to B'' which causes the aircraft 3 to be controlled to the left.

Various modifications of the control systems that are disclosed herein will be apparent to those who are familiar with the general subject matter of the present invention. The number of control circuits that are installed and used in a particular system for operating desired controls at the aircraft 3 can be increased or decreased within practical limits without departing from the scope of the present invention.

A modification in the frequency selector 5 part of the present invention, wherein a plurality of relays operate to perform the function of the stepper relay 32, is illustrated in Fig. 3 of the accompanying drawing. In the circuit there shown, a coded beacon 40 that is provided with a receiving antenna 41 and a transmitting antenna 42 serves as a transpondor with respect to the control station 1.

The control operating output from the beacon 40 is applied to an isolation stage comprising a transformer 43 and an amplifier tube 44. The grid of the amplifier tube 44, to which signal from the beacon 40 is applied, is grounded through the secondary of the transformer 43.

Output from the tube 44 passes through series connected primary windings, of a plurality of frequency selective transformers 45-49, inclusive, that are individually tuned as shown to separate and distinct predetermined frequencies. A positive direct current voltage source, such as the +B battery terminal shown, or the like, applies positive plate voltage to the tube 44 through the primary windings of the transformers 45-49, inclusive.

Signals induced into the tuned secondary windings of the transformers 45-49, inclusive, are applied to the grids of a corresponding plurality of detecting electronic tubes 50-54, inclusive, that convert alternating current of the signal from the beacon 40 into direct current for the operation of relays receiving the outputs therefrom. The outputs of the tubes 50-54, inclusive, are fed to a corresponding plurality of the relay windings 55-59, inclusive, that collectively have one terminal in common through which +B' battery supply is fed to the plates of the tubes 50-54, inclusive, as shown. Signals through the tubes 50-52, inclusive, operate locking relays through relay windings 55, 56, and 57, respectively, and signals from the tubes 53 and 54 operate relays associated with windings 58 and 59.

The circuit that is shown in Fig. 3 of the drawings operates somewhat as in the previously described circuit in that signals from the control station 1 are intercepted by the receiving antenna 41 on the beacon 40 and cause the beacon 40 to apply signal through the tube 44 to the frequency selective transformers 45-49, inclusive.

Signals from an emitting beacon antenna 42, provide information to observers at the control station 1 regarding the azimuth, altitude and range of the aircraft 3, and regarding the operations of the controls on the aircraft 3.

The circuit in Fig. 3 is adapted for the use of five different signal tones to which the five transformers 45-49, inclusive, are separately and individually capacity tuned, as shown. The conduction of these five separate signals through the tubes 50-54, inclusive, energize the relay windings 55-59, inclusive, respectively.

The relay windings 55, 56 and 57 are associated with locking relays that are so connected that if any one of these relays is energized, it will lock in and stay locked until one of the other two relays in this group is energized, at which time the energized one of the other two relays will stay locked.

The energizing of any one of the relay windings 55, 56 or 57 causes an individual and unique signal code to be transmitted from the beacon 4 by way of its antenna 42 for the purpose of indicating to an operator at the control station 1 which of the relay coils 55, 56, or 57 has been energized in response to signal from the control station 1. The relay windings 55, 56 and 57 are, in and of themselves, preferably not adapted for directly causing the operation of the particular controls with which they are associated but are adapted for setting contacts through which the operation of the controls is accomplished by supplying current therefor from a suitable direct current source, such as a battery 61 or the like, upon the energization of either of the operative relay windings 58 and 59. The separate energization of the relay windings 58 and 59 supply current to actuate opposite functions depending upon the preset circuit connection of any one of the relay windings 55, 56 or 57, such as right and left, up and down, accelerate and decelerate, and the like.

In the illustrative embodiment of the invention that is shown in Fig. 3, the energization of any or all of the relay windings 55, 56 and 57 preset contacts that establish pairs of circuits to the controls on the aircraft 3 without causing any alteration in the flight course thereof. A desired alteration in the flight course of the aircraft 3 is accomplished by the selective energization of either of the relay windings 58 or 59, that selectively applies electrical energy to one or the other of the two members in each pair of circuits that are established by the energization of any or all of the relay windings 55, 56 and 57.

The energization of the relay windings 55 establishes circuits to a controller, such as an automatic pilot or the like, preparatory to altering the flight course of the aircraft 3 in azimuth toward the right or left. The energization of the relay winding 56 establishes circuits to a controller that is operated in conjunction with an altimeter or the like, preparatory to altering the flight course of the aircraft 3 in elevation, either up or down. The energization of the relay winding 57 establishes circuits to a controller that is operated in conjunction with suitable means for causing a change in the rate of flight, such as for increasing or decreasing the rate of flight of the aircraft 3. The actual alterations in the flight course, rate of flight or other change in the performance of the aircraft 3, is not accomplished until a signal is received from the control station 1 that causes the energization of either the relay winding 58 or the relay winding 59.

Additional transformer-frequency selector amplifier tube relay groups of components that are substantially duplications of the transformer 47, 75

amplifier 52 and relay winding 57 group that forms a part of the circuit that is shown in Fig. 3, may be added to the present circuit for the operation of additional controls, if desired.

In the operation of the modification of the device that is shown in Fig. 3, let it be assumed that the object in flight is to be caused to turn to the left, gain altitude, and then to perform a third operation, such as to accelerate its rate of flight, or the like. Let it be assumed also that the filter secondary windings of the transformers 45, 46, 47, 48 and 49 are tuned to individually pass signals of different frequencies referred to hereinafter as signals O, P, Q, X and Y, respectively, and which signals cause the operation of the relays 55, 56, 57, 58, and 59, respectively.

In conformity with this assumption, the relay windings 55, 56, and 57 are energized by the reception of the signals O, P, and Q, and the relay windings 58 and 59 are energized by the signals X and Y, respectively, throughout. Each application of a signal X or Y causes a predetermined change in the status of the aircraft 3, such as an elevational change in the units of substantially one hundred feet through the operation preferably of an altimeter, and an azimuth change in angle of flight of a predetermined number of degrees by operation preferably of an automatic compass controller.

In conformity with the above assumptions, the sequence of signals that would be emitted from the control station 1 would be in the order O—X—P—Y—Q—X—Y. The initial signal O would be conducted by the transformer 45 and would cause the tube 50 to energize the relay winding 55.

The energization of the relay winding 55 opens contacts G and H and closes contacts I, J, K, and L of the relay associated with the winding 55. The closing of the contact I applies ground through the resistor 60 to the plate of the selector tube 50. The closing of the contact J causes the beacon 49 to emit a signal to the control station 1 indicating the energization of the relay winding 55. The closing of the right and left azimuth contacts K and L applies no power to operate the right and left controls with which they are connected but does set up the connections through which control actuating power can be applied thereto and hence the closing of the contacts K and L alone is ineffectual to change in azimuth the course of flight of the aircraft 3.

The relay contact L is inoperative to cause the aircraft 3 to turn to the left until the arrival of signal of the frequency X. The signal of frequency X passed through the transformer 48 causes the tube 53 to draw more B' + current through the relay winding 58. The energization of the relay winding 58 closes a contact of a relay associated with the coil 58 and applies a predetermined voltage from the battery 61 through the relay contact L to an operative mechanism, not shown, that turns the rudder of the aircraft 3 so that the course of the aircraft 3 is changed toward the left preferably an angle of a predetermined number of degrees. The rudder of the aircraft 3 is normally positioned to cause the aircraft 3 to fly straight ahead in the absence of signal. This concludes the functional azimuth change in flight course of the aircraft 3 in response to the signal sequence O—X in the cited example.

The aircraft 3 is then prepared to change altitude by the emission of a signal P of a predetermined

mined frequency from the control station 1. The reception of signal P by the beacon 40, energizes relay winding 56. The energization of the relay winding 56 causes the operation of the relay contacts that are associated therewith in a manner that is substantially a duplication of the operation of the relay contacts that have been described for the relay assembly that is associated with the relay winding 55. As in the previous example, the arrival of signal P and resultant energization of relay coil 55 sets up the connections for, but does not accomplish the operation of the elevator on the aircraft 3.

The aircraft 3 is then caused to gain altitude by the emission of a signal Y of a predetermined frequency that, in a similar manner, is induced through the selective transformer 49, and that causes the closing of the contact that is associated with the relay winding 59. The closing of the contact that is actuated by the relay winding 59 causes the application of the potential of the battery 61 across the relay contact M that is associated with the relay winding 56, whereupon the altitude of the aircraft 3 is increased to a desired extent that preferably is a predetermined limited unit number of feet, such as one hundred feet, or the like. The relay contact N is closed along with the contact M, and causes signal of a predetermined frequency or pulse repetition rate to be emitted from the antenna 42 of the beacon 40 and that is intercepted by the antenna 2 of the control station 1 to indicate the operation of the relay winding 56. This concludes the functional elevational change in flight course of the aircraft 3 in response to the signal sequence P—Y in the cited example.

The control of the rate of flight of the aircraft 3 is effected in a similar manner by operation of the relay winding 57 and of the desired relay winding 58 or 59 to decrease or to increase, respectively, the rate of flight of the aircraft 3.

The aircraft 3 is returned to normal flight by the release of either of the operating relays 58 or 59 that is accomplished in any desired manner upon the arrival of the aircraft 3 at a preestablished unit change in elevation, azimuth or rate of flight.

Two or more of the circuits including the tubes 21 and 22 in Fig. 2, if preferred, may be combined into a proportional control system. By the proper selection of the values of the inductances of the transformer 12 and of the capacitances of the tuning capacitors 24 and 25, by shunting the capacitors 24 and 25 with suitable resistors, or by the use of other suitable known means, two filters are formed with overlapping characteristics so that within a certain range all frequencies are passed by both filters in varying proportions.

In such a proportional control system, a pair of overlapping filters receives a signal of variable pulse repetition rate, the neutral frequency of the signal is substantially the mid-frequency of the overlap, and the plate circuits of the tubes 21 and 22 would be adapted to proportional control by known methods.

A proportional control system that is contemplated herein may comprise a derived output in the form of the mechanical rotation of a shaft, in which event the rotation of the shaft would be a number of angular degrees from a zero or center position that is proportional to the variation of the pulse repetition frequency from the neutral frequency. In this adaptation, increased signal pulse repetition frequency would cause the rotation of the shaft in one direction

and a decrease in the signal pulse repetition frequency would cause rotation of the shaft in the opposite direction.

One stage of a proportional control system is shown in fragmentary form in Fig. 4 of the accompanying drawings wherein components that are common to both Figs. 2 and 4 bear corresponding numerical designations that are primed in Fig. 4 and that are not primed in Fig. 2 for ease of association therebetween. The plate-cathode circuit of the isolating electronic tube 10' has the primary winding of a transformer 65 in series therebetween. Two secondary windings of the transformer 65, together with their tuning capacitors 66 and 67, provide a pair of frequency selective filters the ends of which are connected to the grids of a pair of gaseous electronic tubes 68 and 69. The direct current bias for these tubes 68 and 69 is obtained from a common bias battery 73 and from two potentiometers 70 and 71 which are connected across another battery 72. The plate current for the tubes 68 and 69 is furnished by an alternating current supply 74. The plate current for the electronic tubes 68 and 69 flows through direct current actuating motors 75 and 76, respectively. The motors 75 and 76 are so connected as to turn in opposite directions when energized. The direct current for the operation of the motors 75 and 76 is obtained by the rectifying action of the electronic tubes 68 and 69 on the alternating current source 74. A dotted line 79 shows a mechanical linkage which connects the potentiometers 70 and 71, the motors 75 and 76, a sector ring 77 and a device to be controlled, in this case a rudder 78 part of the aircraft 3.

Additional pairs of secondary windings coupled to the primary winding of the transformer 65 may be provided, if desired, for the operation of additional controls, such as the elevators, velocity controls, and the like, on the aircraft 3. The additional pairs of such secondary windings that are inductively coupled with the primary winding of the transformer 65 are individually tuned to a further plurality of individual signals. The additional pairs of secondary windings on the transformer 65 are provided with additional pairs of electronic tubes in similar relation and other circuit elements such as are shown in Fig. 4.

The sector ring 77, that is mounted upon and that rotates with the mechanical drive of the rudder 78, comprises a desired plurality of segments that are insulated from each other and that are individually connected to a beacon, such as beacon 4 or the like, to send signals to the control station 1, as in the previously described adaptations of the present invention. The signals may comprise a desired sequence, such as those indicated as a line for a dot and a rectangle for a dash above the ring 77 or the like, where the signal dot dash dot indicates the rudder in the neutral or straight ahead position, two dots and a dash indicates a turn to the left and a dash and two dots indicates a turn to the right in conformity with the letters L and R, respectively, and arrows on the rudder 78.

In the operation of the present invention that is shown in Fig. 4 of the accompanying drawings, a signal is emitted from the control station 1 and is intercepted by the beacon 4 in the aircraft 3 as in the previously described forms of the invention. In response to the signal so intercepted, the beacon 4 applies a signal to the isolation stage tube 10' and to the transformer 65. The condensers 66 and 67 tune the two parts of the secondary winding of the transformer 65 to

serve as filters in the inductive application of individual signals to the grids of the electronic tubes 68 and 69, respectively.

An example of a typical response curve of the two secondary windings of the transformer 65 is shown in Fig. 5, of the drawings. If the pulse repetition frequency is 400 cycles per second, as indicated by the line 66' in Fig. 5, the secondary winding of the transformer 65 that is associated with the condenser 66, will pass a maximum voltage to the tube 68 and no voltage will be impressed on the grid of the tube 69 as indicated by the line 66'. If the pulse repetition frequency is 500 cycles per second, indicated by the line 80 in Fig. 5, equal voltages will be impressed on the grids of the two tubes 68 and 69. If the pulse repetition frequency is 600 C. P. S., as indicated by the line 67' in Fig. 5, no voltage will be impressed on the grid of tube 68 and maximum voltage will be impressed on the grid of tube 69.

At pulse repetition frequencies lying between 400 and 600 C. P. S., as, for example, at the dash line 81 in Fig. 5, the signal response voltage $z-y$ dominates the signal response $x-y$, and proportional voltages will be impressed on the grids of the two tubes 68 and 69 as indicated by the response curves shown in Fig. 5. Bias potentiometers 70 and 71, motors 75 and 76, sector ring 77 and rudder 78 are all connected mechanically to a common drive as shown by the dotted line 79 in Fig. 4. The motor 75, which is energized by plate current in tube 68 will cause counter clockwise rotation of the system shaft. The motor 76, which is energized by plate current in tube 69, will cause clockwise rotation of the system shaft. Bias battery 73 is so chosen that, with the mechanical system at neutral and equal voltages of a value indicated by the neutral pulse repetition frequency 500, as indicated by the line 80 in Fig. 5, applied to the grids of the tubes 68 and 69, there will be no plate current drawn by the tubes. This condition of neutral assumes that the potentiometers 70 and 71 are at their mid-point and consequently battery 72 which is midtapped by battery 73 does not change the bias voltage value due to the battery 73.

Now assume that the pulse repetition frequency at the sending station is changed from 500 to a new value 550 as shown by the dash line 81 in Fig. 5. The grid voltage applied to the tube 68 will be decreased to the value $x-y$ and the grid voltage applied to the tube 69 will be increased to the value $y-z$. The decrease of grid voltage on the tube 68 will not effect its condition of zero plate current but the increase of grid voltage on the tube 69 will cause it to pass plate current through the motor 76. The motor 76 will rotate until it has changed the potentiometer 70 to such a value that it will increase the negative bias on the tube 69 to a value which will no longer allow the flow of plate current in that tube. This mechanical motion of the motor 76 has also decreased the negative bias on tube 68 so that any increase of grid voltage above its new low value will cause that tube to draw plate current. The rotation of the motor 76 has also caused a rotation of the sector ring switch 77 and the rudder 78.

It can be seen from the above that we have now arrived at a unique balance of the system for the pulse repetition frequency 550 C. P. S. and that any further change in this frequency either up or down will cause the whole mechan-

ical system to seek a new unique balance that is associated with the new frequency. The proportionate control system that is so provided permits the disposition of the rudder 78 at any desired predetermined position between its zero setting, that causes the aircraft 3 to fly straight ahead, and its full rudder position that causes the aircraft 3 to alter its course to a maximum extent toward the right or the left of its previous flight course.

In a proportional control device using a system of the described type, one of the difficulties of the coordination of the system is the correlation of the neutral control frequency with the neutral filter response of the controlled equipment in the vehicle or aircraft 3. Factors such as temperature, humidity and the like that are not identical in both the control and in the controlled equipment, commonly tend to destroy coordination. The remote control system that is disclosed herein permits the operator at the control station 1 to compensate properly for lack of coordination by adjusting at will the neutral control frequency that he is using to match that of the controlled equipment as indicated by the proper beacon response.

It is to be understood that the particular circuits and the components and arrangements thereof that have been submitted herewith have been cited for the purposes of illustrating and describing suitable operative embodiments of the present invention and that various modifications, changes and substitutions may be made therein without departing from the present invention as defined by the claims that are appended here-to.

What I claim is:

1. A system for remotely controlling a number of devices, wherein each device has a plurality of alternative modes of operation; said system comprising a control station for sequentially transmitting a plurality of predetermined signals to a controlled station containing said devices; said controlled station including a receiver of said plurality of signals, a plurality of circuits coupled to said receiver, each of which is selective to a respective one of said predetermined signals, means coupled to a first portion of said plurality of circuits for conditioning for operation any one of said devices in response to the reception of a predetermined signal selected by said first portion of plurality of circuits, said first portion including more than one of said circuits, said conditioning means comprising a separate locking relay coupled to each circuit of said first portion, each relay having only one device associated therewith which is conditioned for operation by the actuation of that relay in response to the reception of the predetermined signal selected by the circuit to which that relay is coupled, said relays being connected so that upon actuation of one relay said one relay is locked and a previously locked relay is released, and means coupled to each of the remaining portion of said plurality of circuits for operating that device which has been conditioned in a particular one of said alternative modes in response to the reception of a particular predetermined signal selected by one of said remaining portion of plurality of circuits.

2. A system according to claim 1, further including means at said controlled station for transmitting to said control station a distinct code signal for each relay indicative of that relay

13

being locked, and means at said control station
for receiving said code signals.
